UNITED STATES PATENT OFFICE

122,425

DESIGN FOR A GAME DEVICE

Amos B. Slater, San Francisco, Calif.

Application February 19, 1940, Serial No. 90,350

Term of patent 7 years

To all whom it may concern:

Be it known that I, Amos B. Slater, a citizen of the United States, residing in the city and county of San Francisco and State of California, have invented a new, original, and ornamental Design for a Game Device, of which the following is a specification, reference being had to the accompanying drawing, forming a part thereof.

In the accompanying drawing:

I claim:

The ornamental design for a game device, as shown.

AMOS B. SLATER.
